I. M. PEASE

TRUSS CONSTRUCTION

Filed Feb. 5, 1925

Fig. 1.

INVENTOR:

Isaac M. Pease,

BY Arthur D. Ewald,

ATTORNEY.

UNITED STATES PATENT OFFICE.

ISAAC M. PEASE, OF CINCINNATI, OHIO, ASSIGNOR TO THE OHIO TRUSS COMPANY, A CORPORATION OF OHIO.

TRUSS CONSTRUCTION.

Application filed February 5, 1925. Serial No. 7,116.

My invention relates to trusses, particularly trusses of the so-called hood type. Trusses of the type mentioned are provided with a front pad-supporting member and lateral springs arranged to encircle the thighs of the wearer below the crest of the ilium. These springs are open at the back and carry retaining pads which bear upon the back of the wearer. It has been found that in the fitting of trusses of this type the ordinary construction does not lend itself to proper adjustment, and therefore the rear pads, as well as the rear portions of the spring, cannot be suitably located on the person of the wearer, so as to obviate chafing and ultimate injury an extreme discomfort, to such extent in many cases that the patient is required periodically to discard the truss for a time in order to permit the parts to heal. It is to overcome this objection that the present invention is principally directed.

Other objects of the invention will appear from the following detailed description thereof:

25 In the drawings:

Figure 1 is a perspective of a truss constructed in accordance with this invention.

Figure 2 is a lateral view of the novel adjustable feature of the truss.

30 The numeral 1 indicates the front supporting member of a hood type truss, which is adapted to support one or two remedial pads 2, which may be, and usually are, adjustable in slots in the member 11. Secured to the ends of the members 1 are lateral springs 3, which are formed to fit around the hips of the wearer below the crest of the ilium. Pivots secured to the ends of the springs 3 are extension springs

40 4, the pivotal securing means comprising set screws 5 or any other suitable adjusting and securing means. The back pads 6 are adjustably secured on the free ends of the springs 4 by means of sleeves or clips 7.

45 The springs 3 and extensions 4 are encased in a leather sheathing 8 in the usual manner, said sheathings being provided with openings 9 whereby access is given to the adjusting screws 5.

The use and value of a truss constructed 50 in accordance with the above invention will be apparent to those skilled in the art to which the same appertains. When the truss is placed upon the wearer, the front member 1 and lateral springs 3 are necessarily fixed 55 in their relation to the person of the wearer. In order that the back pads 6, as well as the extension springs 4, may be suitably positioned with respect to the wearer so that said parts will be disposed on the person, 60 contributing most to his comfort and welfare, the extension springs 4 are rotated to the desired position about their pivotal axes, and secured in such adjustment by means of tightening the screws 5. 65

It will be seen that by this construction, therefore, it is possible to accommodate the truss to the individual features of the wearer so as to obviate the possibility of chafing and discomfort. Should they, however, in the 70 course of time, produce soreness or discomfort, it is possible to effect, in the same manner, further adjustment so as to relieve the irritated parts until the same can regain normality without necessitating the temporary discarding of the truss. 75

Having thus fully described my invention, what I claim as new and desire to secure by Letters Patent is:

1. In a truss, in combination with a front 80 pad supporting member, lateral springs secured to said member, and back extension springs pivotally secured to the ends of said lateral springs and adapted for adjustments in a plane transverse to the plane of said lateral springs.

2. In a truss, in combination with a front 90 pad supporting member, lateral springs secured to said member, back extension springs pivotally secured to the ends of said lateral springs and adapted for adjustments in a plane transverse to the plane of said lateral springs, and means whereby the parts may be secured when suitably adjusted.

3. In a truss, in combination with a front 95 pad supporting member, lateral springs secured to said member, back extension springs pivotally secured to the ends of said lateral

springs and adapted for adjustments in a plane transverse to the plane of said lateral springs, and back pads on the ends of said extension springs.

5. In a truss, in combination with a front pad supporting member, lateral springs secured to said member, back extension springs

pivots secured to the ends of said lateral springs and adapted for adjustments in a plane transverse to the plane of said lateral springs, means whereby the parts may be secured when suitably adjusted, and back pads carried by said extension springs.

ISAAC M. PEASE.
